CLAIM

The ornamental design for a display panel with graphical user interface for controlling machine tools, as shown and described.

DESCRIPTION

FIG. 1 is a front view of a display panel with graphical user interface for controlling machine tools showing our new design;

FIG. 2 is a left side elevational view thereof;

FIG. 3 is a top plan view thereof; and,

FIG. 4 is an enlarged view of the icon shown in the display screen thereof.

The broken line showing of the display panel forms no part of the claimed design.

1 Claim, 4 Drawing Sheets
